ABSTRACT OF THE DISCLOSURE

Light sensitive photoresist compositions particularly useful for projection exposure applications include a photo-crosslinkable polymer and novel sensitizers which are bis-pazido cinnamylidene derivatives of cyclic and linear ketones.

BACKGROUND OF THE INVENTION

This invention relates generally to photocrosslinkable polymer compositions and particularly to sensitizers for such compositions which are bis-pazido cinnamylidene derivatives of cyclic and linear ketones.

In the manufacture of miniaturized electrical components it is necessary to form intricate patterns of materials with great dimensional accuracy. In a conventional pattern forming process the substrate layer is coated with a light sensitive composition, or photoresist, which is exposed to a light image. The solubility characteristics of the resist are changed by the exposure and a relief image is formed by removing, with a suitable solvent, either the exposed or the unexposed portions of the resist depending upon whether a positive or negative resist is employed. The remaining resist masks portions of the substrate and the exposed portions can then be treated to form the desired circuit patterns and components as by etching, coating, impregnation or other techniques which are well known in the art.

Generally, a contact printing technique is used to expose the resist wherein a printing mask is placed in contact with the resist layer and the layer exposed to actinic radiation through the open portions of the mask. The mask used to form the intricate patterns are expensive to manufacture and must be reused many times. A disadvantage of the contact printing process is that contact between the mask and substrate can result in either physical damage to the delicate patterns on the mask or the physical transfer of resist to the mask. In any event, the contact results in gradual wear of deterioration of the mask so that it becomes unusable. It would be desirable, therefore, to employ a non-contact or a projection printing process, to avoid mask damage. Practical lens systems for projection exposure are relatively opaque to ultra-violet radiation. Unfortunately, most photoresist compositions having the required speed for practical use are only sensitive in the shorter wavelengths and thus required actinic radiation in the ultra-violet range. For example, polymers sensitized with bis-pazidobenzylidene ketones such as those described in Sagura et al. Pat. 2,940,853 have little or no absorption at about 4000 Å. at film thicknesses below two microns.

BRIEF DESCRIPTION OF THE INVENTION

We have now discovered a new class of azide derivatives of cyclic and linear ketones which in combination with light sensitive polymers give thin film resist compositions having very fast speeds and an extended range of sensitivity making the compositions suitable for projection printing using conventional lens systems.

In accordance with this invention a light sensitive mate-

2

rial is provided comprising a photo-crosslinkable polymer and a bis-pazidocinnamylidene ketone. Preferred ketones have the general formula:

where

- 10 R₁ is hydrogen or alkyl, where
R₂ is hydrogen or alkyl, and where
R₁ and R₂ may be joined to form a cyclic, aliphatic ketone
having 4 to 6 carbon atoms in the ring.

DESCRIPTION OF THE DRAWINGS

The figure is a graph of wave length versus percent absorption of a composition of the invention compared with a light sensitive composition of the prior art.

DETAILED DESCRIPTION

20 Photo-crosslinkable polymers of the type useful in resist compositions of the invention are well known to those skilled in the art and include for example cyclized polyisoprene, polyvinylpyrrolidone, polyvinylcinnamate, poly(vinylcinnamylidene acetate), isopropyl polystyrene, polybutadiene, polyisobutylene, polysiloxane, etc.

25 The novel sensitizers of the invention are bis-pazidocinnamylidene ketones. Preferred ketones have the general formula:

- 35 where R₁ is hydrogen or alkyl, where R₂ is hydrogen or alkyl, and where R₁ and R₂ may be joined to form a cyclic aliphatic ketone having 4 to 6 carbon atoms in the ring. It should be understood that the scope of the invention includes closely related compounds such as carbonyl azido cinnamylidene and sulfonyl azido cinnamylidene derivatives.

40 Representative compounds of the invention include, for example, 2,6-bis-(pazidocinnamylidene)-4-methyl cyclohexanone; 2,6-bis-(pazidocinnamylidene) cyclohexanone; 1,9-bis-(pazidophenyl)-1,3,6,8-nonatetraene-5-one.

45 The sensitizers of the invention are employed by mixing them with a light sensitive polymer in a suitable organic or aqueous-solvent system. Alternatively, it is possible to graft the ketones onto a suitable polymer chain to provide a self-contained light sensitive polymer resist.

50 Relative proportions of polymer and sensitizer may be varied as conditions require but generally the sensitizer will be present in approximately from one to twenty percent by weight based on the weight of polymer with the preferred range being one to ten percent. The solids content of the polymer-sensitizer solution will range from about one to forty percent by weight. Typical solvents include the lower alcohols such as methanol, ethanol, propanol; ketones such as cyclohexanone, 2-butanone, acetone; dimethylformamide, tetrahydrofuran, pyridine, benzene, toluene, etc. and mixtures thereof.

55 Conventionally, the film forming photosensitive compositions are coated on the substrate by any of the conventional methods well known in the photoresist art which can include dipping, spraying, spin coating and so forth. After application of the coating the solvent is driven off as by evaporation, to leave a thin coating of the photo-sensitive composition on the support. The coating may then be exposed imagewise to radiation through an ordinary lens projection system passing through a suitable mask or other conventional means wherein the light struck

portions of the dry resist pattern will become insolubilized exposing radiation of wavelengths of 4000 Å. or above thicknesses at which the insolubilization will occur using exposing radiation of wavelengths of 400 Å. or above can be as low as .3 micron. Thicker films can be used to a point beyond which the desired resolution is not obtained. For a 2.5 micron line width an optimum resist thickness is about .5 micron.

After the exposure induces photopolymerization or insolubilization of the coating in the exposed areas, the image is developed by treating the coating with a suitable solvent which removes the non-light struck areas of the coating. Conventional pre and post baking steps can be employed in order to enhance the resolution of the exposed areas.

The novel compositions of the invention can be prepared by reacting the corresponding cinnamaldehyde with the ketone. The p-azidocinnamaldehydes can be prepared by diazotization of 4-aminobenzaldehyde followed by treatment with sodium azide. For example, by the process described by M. L. Forrester and H. M. Judd, JCS 97 pg. 254 (1910), the p-azidobenzaldehyde is then reacted with acetaldehyde to form the p-azidocinnamaldehyde which is then reacted with the desired ketone, for example, cyclohexanone to obtain a cyclic ketone derivative or with acetone to obtain a straight chain derivative.

The invention is further illustrated by but is not intended to be limited by the following examples wherein parts are by weight unless otherwise indicated.

EXAMPLE 1

Preparation of 2,6-bis(p-azidocinnamylidene)-4-methylcyclohexanone

In a round bottom flask equipped with a stirrer, condenser and thermometer, 20 grams of p-azidobenzaldehyde and 32 grams of acetaldehyde were slurried together. Keeping the reaction mixture at about 0° C. there was added stepwise 2 milliliters of a 20% solution of potassium hydroxide in methanol. After stirring for one hour, sixty-four milliliters of acetic anhydride were added and the reaction mixture was heated on a steam bath for one hour. The reaction mixture was then poured into a solution of 64 ml. of concentrated hydrochloric acid in 480 ml. of hot water, and the stirring and steam heating continued for an additional 15 minutes. After cooling, the reaction mixture was ether extracted, the ether extract washed with sodium acetate solution, and dried over sodium sulfate. The ether was evaporated and the oil that remained recrystallized from ether by cooling in a "CO₂-acetone" bath.

The resultant yellow crystals of p-azidocinnamaldehyde melted at 71-73° C. The structure was confirmed by nuclear magnetic resonance spectrometry and the purity determined thin layer chromatography and by elemental analysis. The p-azidocinnamaldehyde obtained in this manner weighed 6 grams: Calculated for C₉H₇N₃O: C, 62.42; H, 4.07; N, 24.27. Found: C, 62.24; H, 4.02; N, 24.22.

A solution of 0.6 grams of 4-methylcyclohexanone, 2.0 grams of the p-azidocinnamaldehyde prepared above and about 0.5 ml. of a 25% by weight aqueous sodium hydroxide in 75 ml. of ethanol was stirred in a round bottom flask at room temperature for 3½ hours. The reaction mixture was then filtered and the precipitate collected. The orange-yellow solid was recrystallized from acetic acid, and weighed 0.9 grams. NMR spectrometry proved the structure to be 2,6 bis(p-azidocinnamylidene)-4-methylcyclohexanone and thin layer chromatography and elemental analysis determined it to be pure. Found: carbon 71.08, hydrogen 5.26, nitrogen 19.70. Calculated for C₂₅H₂₂N₆O: carbon 71.07; hydrogen 5.24; nitrogen 19.89.

EXAMPLE 2

Preparation of 2,6-bis(p-azidocinnamylidene)cyclohexanone

5 This compound was prepared by an analogous method to the method used in Example 1. The formulation used in the final condensation was:

10 0.6 gram of cyclohexanone
2.0 grams of 4-azidocinnamaldehyde
75 ml. of ethanol
0.5 ml. of 25% aqueous sodium hydroxide

The reaction was carried out in the same manner except that the compound was recrystallized from a mixture of 15 toluene and 30-60 petroleum ether. The product, which was shown to have the correct structure by NMR, was determined to be pure by thin layer chromatography and elemental analysis. Calculated for C₂₄H₂₀N₆O: carbon, 70.57; hydrogen, 4.93; nitrogen, 20.57. Found: carbon 20 70.29; hydrogen, 4.71; nitrogen 20.50.

EXAMPLE 3

Preparation of 1,9-bis(p-azidophenyl) 1,3,6,8-nonatetraene-5-one

25 The compound was prepared by a method analogous to the method of Example 1 with the following reagents being employed in the final condensation:

30 2 grams of p-azidocinnamaldehyde
0.4 gram of acetone
50 ml. of ethanol
0.16 gram of sodium hydroxide in 3 ml. of water

35 The reaction was carried out at room temperature for 4 hours. The precipitate was filtered, water washed and dried. It weighed 0.85 grams and was shown to have the correct structure by NMR. Purity was established by thin layer chromatography and elemental analysis. The 40 compound decomposed on heating at 136° C. Calculated for C₂₁H₁₆N₆O: carbon 68.47; hydrogen 4.37; nitrogen 22.81. Found: carbon 68.49; hydrogen 4.24; nitrogen 22.31.

EXAMPLE 4

45 In order to illustrate the improved speed and spectral response of photoresist compositions containing the novel photosensitizing compositions of the invention, formulations of a negative photoresist were prepared. A photoresist composition A was prepared by dissolving 10 grams 50 of cyclized poly-cis-isoprene (Goodyear NR) and 0.15 gram of 2,6 bis(p-azidocinnamylidene)-4-methylcyclohexanone in 80 ml. of xylene. A second resist formulation B according to the prior art contained about 27% 55 by weight of liquid resist of cyclized poly-cis-isoprene and 1.7% by weight of liquid resist of 2,6 bis(p-azidobenzylidene)-4-methyl-cyclohexane dissolved in 100 ml. of a solvent mixture consisting of about 5% methyl cellulose, 12% benzene, and 82% xylene.

60 Each solution was coated to solid thicknesses of 0.5 microns and 1.2 microns on thermally oxidized silicon wafers (5 samples of each resist at each thickness) and the sensitivity of the resists determined at various wavelengths. The sensitometric procedure and equipment employed were similar to those described by M. Htoo in the 65 Journal of Photographic Science and Engineering, volume 12, Number 3, pages 169-174, May-June 1968. The shutter was modified by replacement with an Ilex guillotine shutter to allow increments of time exposure to be made on each wafer.

70 The coated wafers were prebaked at 95° C. for 5 minutes, exposed for a series of time (2-10 seconds) with one sample of each lot being used to find the minimum time of exposure to obtain an image, developed for two minutes in xylene, and etched in HF to test the adhesion 75 and etch resistance of the resist. The intensities of the ex-

posure wavelengths were measured with a calibrated thermopile.

The speed or sensitivity of each lot was calculated from the minimum exposure energy found which is defined as the amount of energy (Intensity $\times$ time = ergs/cm.²) necessary to produce a good quality image which can withstand the HF etch. The speed or sensitivity is defined as the reciprocal of energy, times an arbitrary constant K; or $S = K/\text{energy} = K/\text{ergs/cm.}^2$, where K is chosen as 10⁷ to keep the values in small round numbers. The results are shown in Table I below:

TABLE I

Resist	Thickness, microns	Sensitivity 10 ⁷ /ergs/centimeter ²		
		3,650 Å.	4,050 Å.	4,350 Å.
A -----	0.5	1,430	1,000	420
A -----	1.2	1,250	950	330
B -----	0.5	164	95	6.5
B -----	1.2	156	90	21

As shown from the results listed in Table I the composition A of the invention gave approximately a 10 fold speed increase over the composition B of the prior art at the resist thicknesses shown which are needed for fine resolution and the composition showed sufficient sensitivity in the 4000 Å. to 4350 Å. wavelength range to make it extremely useful for projection printing. Because of the multiple exposures needed for projection printing the speed increase results in a vast reduction in throughput time. The drawing shows the absorption of compositions A and B as measured on a Beckman DK-2 spectrometer.

EXAMPLE 5

A resist composition was prepared by dissolving 10.0 grams of polyvinylpyrrolidone (molecular weight about 100,000, GAF) 0.1 gram of 2,6 bis(p-azidocinnamylidene)4 - methylcyclohexanone in 100 ml. of methylcelulose acetate. The composition was coated on a silicon wafer substrate using the conventional spin coating technique to a dry thickness of 5000 Å. The substrate and resist was exposed to a projected light image at 4050 Å. for one second and then developed using Cellosolve acetate as a solvent. The resulting developed image was sharp and showed excellent line definition (2.5 micron width). Similar exposures of the resist formulation B of Example 4 were made using the projection exposure system at a wavelength of 4050 Å. for increasing periods of time. No image was formed even after an exposure for 100 seconds.

EXAMPLE 6

A resist formulation was made by dissolving 10.0 grams of polyvinyl cinnamate and 0.1 gram of the sensitizer 2,6 bis(p-azidophenyl)1,3,6,8-nonatetraene-5-one dissolved in 100 ml. of cyclohexanone. The resists were coated in a thickness of 1 micron by conventional spin coating technique and exposed using a projection apparatus which was a Mann Model 1595 Step and Repeat Camera at a wavelength of 4050 Å. for 0.3 second. After development with a solvent comprising sharp images having excellent resolution were obtained.

It was found that an even greater speed increase could be obtained by heating the resist compositions to a maximum temperature at least 10° below the decomposition temperature of the sensitizer during the exposure of the resist.

While the invention has been particularly shown and described with reference to preferred embodiments there-

of, it will be understood by those skilled in the art that the foregoing and other changes in form and details may be made therein without departing from the spirit and scope of the invention.

5 What is claimed is:

1. A photoresist composition comprising a mixture of a photo-crosslinkable polymer and a bis-p-azidocinnamylidene ketone.

10 2. A photoresist composition comprising a mixture of a photo-crosslinkable polymer and a bis-p-azidocinnamylidene ketone having the general formula

where

R₁ is hydrogen or alkyl, where

R₂ is hydrogen or alkyl, and where

20 R₁ and R₂ may be joined to form a cyclic aliphatic ketone having 4 to 6 carbon atoms in the ring.

25 3. The composition of claim 2 wherein the ketone is 2,6-bis(p-azidocinnamylidene) 4-methylcyclohexanone.

4. The composition of claim 2 wherein the ketone is 2,6-bis(p-azidocinnamylidene)cyclohexanone.

25 5. The composition of claim 2 wherein the ketone is 1,9-bis(p-azidophenyl)1,3,6,8-nonatetraene-5-one.

30 6. A photoresist coating composition comprising a light sensitive polymer and from about 1 to about 30 percent by weight based on the weight of polymer of a bis-p-azidocinnamylidene ketone said polymer and sensitizer being dissolved in an organic solvent in amounts to produce a solution having a solids content of from about 1 to 40 percent by weight of the total weight of solution.

35 7. The coating composition of claim 6 wherein said ketone has the general formula

where

R₁ is hydrogen or alkyl, where

R₂ is hydrogen or alkyl, and where

45 R₁ and R₂ may be joined to form a cyclic aliphatic ketone having 4 to 6 carbon atoms in the ring.

50 8. The coating composition of claim 7 wherein said polymer is cyclized poly-cis-isoprene, said ketone is 2,6-bis(p-azidocinnamylidene)4 - methylcyclohexanone and said solvent is xylene.

55 9. A photoresist element comprising a layer including a mixture of a light sensitive polymer and a bis-p-azidocinnamylidene ketone supported on a substrate.

10. The element of claim 9 wherein the layer has a thickness of from 0.3 to 2 microns.
